Inventor

Charles A. Pilger.

By Mason Fenwick Lawrence.
Attorney

UNITED STATES PATENT OFFICE.

CHARLES A. PILGER, OF SCRANTON, PENNSYLVANIA.

ROPE FRICTION SEPARATOR DEVICE.

Application filed April 7, 1923. Serial No. 630,601.

To all whom it may concern:

Be it known that CHARLES A. PILGER, a citizen of the United States, residing at Scranton, in the county of Lackawanna and 5 State of Pennsylvania, has invented certain new and useful Improvements in Rope Friction Separator Devices; and he does hereby declare the following to be a full, clear, and exact description of the invention, such as 10 will enable others skilled in the art to which it appertains to make and use the same.

This invention relates to attachments for silk looms, and more particularly to a rope friction separator device.

15 The object of the present invention is to provide a device of the character indicated which will operate to hold the warp-beam of a silk loom firmly in position; prevent the ropes from getting crossed; and provide a 20 steady friction upon the ropes, eliminating the necessity for the use of powder, and thus prevent scheiers or barry marks in the cloth.

25 The invention consists in the novel construction arrangement and combination of parts as hereinafter more particularly described and claimed.

30 One sheet of drawings accompanies this specification as part thereof in which like reference characters indicate similar parts throughout.

Fig. 1 is a fragmentary perspective view showing the warp-beam of the silk loom with the present invention applied.

35 Fig. 2 is a side elevation of the improved device removed from the loom and partially broken away.

Fig. 3 is a vertical transverse sectional view taken on the lines 3—3 of Fig. 2.

40 It is now common practice to operate the warp-beam of a silk loom by means of the frictional engagement of a rope spirally wound on a pulley attached thereto. To secure the proper frictional engagement of this rope with the pulley, friction powders 45 are used but these are objectionable and there is also an objectionable tendency of the rope spirals to cross and thus make the operation of the warp-beam uneven.

50 In accordance with the present invention, a semi-cylindrical body (1) is provided, having formed upon its inner or concave face a plurality of flanges (2) spirally or helically disposed on a common axis with that of the said concave face.

The outer face of the body (1) is provided with a flat bearing surface (5) preferably formed on a projection (4) and adapted to rest against an arm (6) of an angle bar secured thereto as by bolt (8) 60 passed through a suitable slot (7) provided in the angle bar. The other arm (9) of the angle bar is provided with a slot (10), the inner edge of which is undercut as at (11) to receive the head (12) of a bolt (13) by 65 means of which the angle bar may be adjusted relative to the frame of the loom (14). If desired, the angle bar may be further provided with a slot (17) adapted to receive a suitable feather to restrict its adjustment 70 relative to the frame of the loom (14).

In operation, the improved device is secured to the frame of the loom as illustrated in Fig. 1, being adjusted both vertically and horizontally relative thereto by 75 reason of the slot previously described and with the body (1) disposed over the face of the pulley (15) with the flanges (2) interposed between the successive turns of the rope (16). It will be obvious that the frictional engagement of the device with rope 80 (16) may be adjusted as desired by means of bolts (8) and (13), and it will effectually prevent crossing of the ropes on the pulley.

Having thus fully described my invention, 85 I claim:

1. A rope friction separator in combination with a driving pulley of a loom, comprising a concaved body portion provided with a plurality of spaced ribs conforming 90 to and extending longitudinally upon the concave face of the body.

2. A device as specified in claim 1 with means for adjustably securing the same to the frame of a loom. 95

3. A rope friction separator in combination with a driving pulley of a loom, comprising a concaved body, provided with a rib upon its concave face helically disposed relative the axis thereof. 100

4. A device of the character described comprising in combination a body having a concave cylindrical face, a bracket adjustably secured to the body and a plurality of spaced parallel helically disposed ribs upon and concentric with the concave face of the body. 105

In testimony whereof I affix my signature.

CHARLES A. PILGER.
